UNITED STATES PATENT OFFICE.

ABEILARD SANTA ROSA ARAUJO, OF RIO DE JANEIRO, BRAZIL.

FIRE GRATE.

Application filed November 2, 1926, Serial No. 145,740, and in Brazil November 25, 1925.

The present invention has reference to improvements in fire grates and relates more particularly to a grate of the shaking type composed of alternately disposed stationary 5 and slidingly reciprocable grate members, and its object is to provide a shaking grate which can be operated with a high degree of efficiency with a relatively small expenditure of force and which is especially adapted for 10 use with rather inferior fuel material tending to cake and yielding a large amount of residue.

The invention essentially comprises a grate, preferably of the sectional type, in which a 15 reciprocably-movable bar is disposed between each two stationary grate bars, and in which the sets of grate bars present relatively staggered fuel-engaging humps. In a preferred embodiment of my invention the 20 humps of the slideable bars are extended laterally over the respectively flanking stationary bars and are positioned intermediate the humps of the latter, and in operation act on the stationary bars in the manner of 25 scrapers and fuel turners, as will be fully described further on. The shaking operation is effected by relatively displacing only approximately one-half of the total grate area.

In order to make my invention more readily 30 understood, I will now describe it in detail in connection with the accompanying drawing, in which Fig. 1 shows one of the stationary grate bars in side elevation; Fig. 2 is a longitudinal section therethrough; Fig. 3 is a 35 side view of one of the reciprocating grate bars, of which Fig. 4 is a plan view. Fig. 5 is a fragmental side view, in more or less diagrammatic showing, of the assembled grate structure; Fig. 6 is a plan view thereof 40 with the dead plate 8 and the part to which it is attached omitted; Fig. 7 is a cross-section through one movable and two stationary bars, on line 7—7 of Fig. 5; and Fig. 8 is a similar section through a modification.

The stationary portion of the grate is composed of front and rear cross-supports 1 and intermediate longitudinal supports 2, suitably mounted on the furnace bed 3. The 45 grate bars are partly fixed and partly slidingly reciprocable. The stationary bars 4, shown in Figs. 1 and 2, are preferably of the air-cooled type and present a median hump 5 and the terminal half-humps 6 respectively. The notched half-humped extremities are 50 hung upon the grate supports 7 extending from the supports 1 in a well known manner,

as shown in Fig. 5. The extremities of the bars are preferably extended toward the fire door and the bridge respectively, to cooperate at these points with separate dead plates 60 8, for preventing loss of fuel during the shaking operation. The arrangement described thus far does not differ from the prior art.

The movable portion of the grate is composed of cross-braced supporting frames 9, 65 the number of which depends upon the number of sections in which the grate is subdivided. Each frame 9 is mounted for rolling movement on rollers 10 journaled in the supports 2 so that it can freely be reciprocated relative to the stationary parts in a direction toward and away from the fire door. In the frame 9 the individual shaker bars 11 (Figs. 3 and 4) are suitably supported, for 70 instance by means of the cross-supports 111. 75 Each bar 11 is in the form of a preferably air-cooled hollow body from which extend upwardly the humped portions 12, so disposed that they lie intermediate the humps 5 and 6 of the respectively adjacent stationary bars 80 4. These humps 12 are laterally extended beyond the vertical planes of the body sides and project partly over the flanking bars 4, as shown in Figs. 6 and 7.

For relatively reciprocating the movable 85 grate unit I may employ various means, hand or power operable. By way of example I have shown a hand operable device. The handle 13 operates the cranked link 14, of which there may be several depending upon 90 the number of sections into which the grate is divided, to which the outer end of the link or links 14 are pivotally secured. The movable bars then move to and fro between the two flanking stationary bars, in close relation 95 therewith but not in actual contact, whereby the fuel resting upon the grate as a whole is alternately moved up against the stationary humps or away from them, which causes a thorough shaking up, aerating and scraping 100 off thereof.

The arrangement, obviously, is not restricted to the use of horizontal grates, but may also be used in grates of the inclined type. The walls of the grate members are thin to 105 allow of thorough cooling, which tends to prevent caking of the fuel on the grate surface. The humps 12 of the shaker bars may be cast integrally with the bar body, or they may be individually attached thereto in suitable manner.

Instead of providing the laterally extend-

ing scraper humps 12 on the movable bars, I may, as shown in Figure 8, reverse the described arrangement and arrange broad humps 120 on the fixed bars 4, extending respectively partly over the uniformly cross-sectioned shaker bars between their narrow humps, the shaking and scraping effect being practically the same, as in the first described arrangement.

10. What I claim is:—

1. A grate structure of the character described, comprising a plurality of stationary bars comprising single side bars and a plurality of pairs of bars arranged therebetween and spaced therefrom and from each other, each of said bars having upon its top a central hump and an end half-hump, a shiftable bar arranged between each of said pairs and between each side bar and the adjacent pair, 15 a pair of upstanding bodies carried by each shiftable bar and projecting beyond each side in overlying relation to and arranged between the center hump and an end half-hump of an adjacent stationary bar, and means for reciprocating the shiftable bars in unison, 20 said shiftable bars each being in the form of an elongated open frame to provide an air cooling action.

2. A grate structure of the character described, comprising a plurality of stationary bars comprising single side bars and a plurality of pairs of bars arranged therebetween and spaced therefrom and from each other, 25 each of said bars having upon its top a central hump and an end half-hump, a shiftable bar arranged between each of said pairs and between each side bar and the adjacent pair, a pair of upstanding bodies carried by each shiftable bar and projecting beyond each side in overlying relation to and arranged between the center hump and an end half-hump of an adjacent stationary bar, and means for reciprocating the shiftable bars in unison.

3. A grate structure of the character described, comprising a set of stationary bars comprising single side bars and a plurality of pairs of bars arranged therebetween and spaced therefrom and from each other, each of said bars having upon its top a central hump and an end half hump, a set of shiftable bars comprising a single bar arranged between each of said pairs of stationary bars and between each side bar and the adjacent pair of stationary bars, the bars of one set having laterally extending scraping projections partially overhanging the upper surfaces of the adjacent bars of the other set, and means for reciprocating the shiftable bars in unison.

each of said bars having upon its top a central hump and an end half-hump, a shiftable bar arranged between each of said pairs and between each side bar and the adjacent pair, 35 a pair of upstanding bodies carried by each shiftable bar and projecting beyond each side in overlying relation to and arranged between the center hump and an end half-hump of an adjacent stationary bar, and means for reciprocating the shiftable bars in unison, 40 said shiftable bars each being in the form of an elongated open frame to provide an air cooling action.

3. A grate structure of the character described comprising comprising a set of stationary bars comprising single side bars and a plurality of pairs of bars arranged therebetween and spaced therefrom and from each other, each of said bars having upon its top a central 45 hump and an end half hump, a set of shiftable bars comprising a single bar arranged between each of said pairs of stationary bars and between each side bar and the adjacent pair of stationary bars, the bars of one set having laterally extending scraping projections partially overhanging the upper surfaces of the adjacent bars of the other set, 50 and means for reciprocating the shiftable bars in unison.

In testimony whereof I affix my signature.

ABEILARD SANTA ROSA ARAUJO.
